UNITED STATES PATENT OFFICE.

HENRY F. BECHMAN, OF BATTLE CREEK, MICHIGAN, ASSIGNOR TO THE DUPLEX PRINTING PRESS COMPANY, OF BATTLE CREEK, MICHIGAN.

TRIPLEX PRINTING-PRESS.

No. 867,232.

Specification of Letters Patent.

Patented Oct. 1, 1907.

Application filed January 3, 1905, Serial No. 239,419. Renewed March 4, 1907. Serial No. 360,498.

To all whom it may concern:

Be it known that I, HENRY F. BECHMAN, of Battle Creek, in the county of Calhoun and State of Michigan, have invented certain new and useful Improvements 5 in Triplex Printing - Presses; and I hereby declare that the following is a full, clear, and exact description thereof, reference being had to the accompanying drawings, which form part of this specification.

This invention is an improvement in printing presses, 10 and relates particularly to 12 page flat bed web presses of the duplex type, which I shall denominate a "triplex" press, wherein three horizontal type beds are arranged parallel, one above the other, and three reciprocating impression cylinders are employed, one for 15 each bed.

The present invention relates particularly to the manner of and means for threading a wide web and a narrow web through such "triplex" press in such manner that a wide web may be printed on two beds, and a 20 narrow web printed and perfected on another bed.

The invention will clearly be understood from the following description and drawings, and the essential features thereof for which protection is desired are set forth in the claims.

25 In the drawings—Figure 1 is a longitudinal sectional diagram through a complete "triplex" flat bed press embodying the invention. Fig. 2 is a detail plan view thereof showing the means for turning the narrow web.

The press has three horizontal type beds A, A', A' 30 arranged parallel, and one above the other in vertical alinement. Co-acting with these beds are laterally reciprocating cylinders a, a', a'. The main or four-page-wide web W is led in from the roll through the feeding-in rolls 1 under suitable guide 2, to and over

35 a movable looping roller 3, thence under guide 2^b, to and over suitable guides and between the bed A and cylinder a, then under and over suitable guides to and between the bed A' and cylinder a', back over upper guide 2^b, down under upper looping roller 3^a, of the lower 40 pair of looping rollers and thence up over suitable guides to the delivery rollers 1^a where it is longitudinally divided, one part W' passing direct to the guide f' into the folder, and the other part W² passing over deflecting rollers and bars until it is brought into line with and 45 beneath part W', and then passes over guide f into the folder.

The parts so far shown and described for operating web W are substantially similar in construction and mode of operation to like parts in the well known duplex press, and when a full width web is used, the product of the two lower printing couples is an eight page news-paper.

The second narrow or half-width web w, is led from the roll at the rear end of press, up over a guide 4, forward (over and above the uppermost bed) to and around

a feeding roll, with which coöperate feed tapes 5^b; web w passing thence over a guide 4^a and under a guide 4^b, to and over a looping roller 3^c down under a guide 4^c, thence backward above cylinder a' to a guide 4^d at the rear of the press, under such guide and forward between 60 bed A² and cylinder a² to and over a guide 4^e, being imprinted on one side during this first passage between bed A² and cylinder a². From roller 4^e the web passes down under a looping roller 3^b, to and over a guide 4^f and then to a feed-out roll 5^b, assisted by tapes 5^c, and 65 passes thence under a guide 10 up over a guide 11, over an angle bar 12, to and over a roll 13, back over another angle bar 14, to and over a roller 15, and then back to and over roller 16 down under feed roll 5, to and over roll 4^a down and around roll 4^b over looper 3^c under guide 4^e back over guide 4^d, forward again between 70 bed A² and cylinder a² to roller 4^e, under looper 3^b, over guide 4^f to feed roll 5^b, where delivery tapes 5^c contact, then to and under guide 10, up over a guide 17 and thence over roller f² to the folder, being super- 75 imposed on the webs W', W² and folded therewith as one web in the folder.

The web w enters the press at the right hand side of the machine, and during its first passage between the bed and cylinder, is printed on one side by forms arranged at the far, or left hand, side of bed A²; it then passes through the deflector and turner (composed of the bars 12 and 14 and rollers 13 and 15), by which it is shifted to the near side of the machine, so that the second passage length of web w in the press between the 80 bed and cylinder A², a², lies parallel with the first length of web w therein, and receives its second or perfecting impressions from forms placed at the near or right hand side of bed A².

It will be observed that both lengths of web w passing 90 between bed A² and cylinder a², move in the same direction and time and are operated by the same feeding, looping, guiding and delivering devices. It will also be observed that the web w is not turned in the press; by that I mean between the points of its first in-feed and 95 first delivery, but instead is turned and deflected between the points of its first delivery and second in-feed; this method of threading and turning is of great practical importance, for if the web is turned or deflected in the press so that it has to be shifted over the deflector or turner by the action of the looping devices, the danger of rupturing the web is much enhanced, and the speed of operation correspondingly restricted; but by turning and deflecting the web out of the press, or between the points of first delivery and second in-feed thereof, I am 100 enabled to keep it moving continuously through the turning and deflecting devices without the alternate stoppage and starting or acceleration and retardation of movement imparted to that part of the web subject to the action of the looping rollers. By reason of such 105 110

uniform continuous movement I can run the web with safety at much greater speed than is permissible when the web is turned or deflected while under the influence of the looping devices.

5 The several looping rollers 3, 3^a, 3^b, 3^c, are preferably all mounted on a common frame or carrier L vibrated by levers L¹ operated by cams L² as in the ordinary duplex press; and the cylinders a, a', a'', may be journaled in a single set of cross heads and reciprocated by pitman and 10 crank wheels, as in the ordinary duplex press. The particular means for operating the looping rollers and cylinders are not features of the present invention and will be readily understood by those skilled in the art. Of course the several sets of feeding, web looping, and 15 delivering devices are all arranged to operate synchronously so that equal lengths of both webs will be fed in and delivered from the machine in the same times, and the product of the press, operated to its full capacity, will be twelve page news-papers; eight pages being 20 produced from web W on the two lower beds and cylinders, and four pages from web w on the upper bed and cylinder.

I do not restrict myself to printing a full width web on the two lower beds, and a half width web on the upper bed, although this is the preferred construction and 25 arrangement of parts.

Having thus described my invention what I claim as new and desire to secure by Letters Patent is:—

1. In a printing press, the combination of a plurality of 30 printing couples each comprising a bed and co-acting cylinder, means for feeding a web twice in the same direction to one printing couple, means for delivering such web twice from said printing couple, and means for turning and deflecting such web between the point where it is first delivered from such couple by the delivery means and the 35 point where it is a second time fed thereto by the feeding means; with means for directing another web through the other printing couples to be printed thereby, substantially as described.
2. In a printing press, the combination of a plurality of 40 printing couples, each consisting of a bed and co-acting cylinder, means for feeding a narrow width web twice in the same direction to one printing couple, means for delivering such web twice from said printing couple, and means 45 for turning and deflecting the web between the point where it is first delivered from such couple and the point where it is a second time fed thereto; with means for directing a full width web through the other printing couples to be perfected thereby, substantially as described.
3. In a flat bed web printing press, the combination of 50 a plurality of printing couples each comprising a bed and co-acting cylinder, means for feeding a narrow width web twice into one printing couple, means for delivering such web twice from such couple, means for directing it twice in the same direction through such couple, and means for deflecting and turning such web between the point where it is first delivered from such couple by said 55 delivery means and the second time fed thereto by said feeding means; with means for feeding a full width web to the other printing mechanism to be perfected thereby, substantially as set forth.
4. In a flat bed web printing press, the combination of a 60 plurality of printing couples, arranged one above the other, each consisting of a stationary bed and reciprocating impression cylinder, means for feeding a narrow width web twice into one printing couple, means for delivering

such web twice from such couple, means for directing it twice in the same direction through such couple, and means for deflecting and turning such web between the point where it is first delivered from such couple and the 70 second time fed thereto; with means for feeding a full width web to the other printing couples, means for directing the web therethrough to be perfected thereby, and means for delivering it therefrom, substantially as set forth. 75

5. In a printing press, the combination of three printing couples arranged one above the other, each consisting of a bed and co-acting cylinder, means for directing a full width web between the two lower beds and cylinders, and means for directing a narrow-width web twice between the upper 80 bed and cylinder, substantially as and for the purpose described.

6. In a printing press, the combination of three printing couples arranged one above the other, each consisting of a bed and co-acting cylinder, means for directing a full 85 width web between two of the printing couples, and means for directing a narrow-width web twice between the third printing couple, substantially as and for the purpose described.

7. In combination, three printing couples each comprising a stationary bed and co-acting reciprocating impression cylinder, said couples being arranged parallel one above the other; with means for feeding a full width web between two of the printing couples, to be perfected thereby, means for feeding a narrow width web twice through 90 the other printing couple, and means for deflecting and turning the narrow web so it will be perfected by said couple, substantially as and for the purpose described. 95

8. In a "triplex" flat bed printing press, the combination of three stationary beds and co-acting reciprocating impression cylinders arranged parallel one above the other; with means for feeding a full width web between the two lower beds and cylinders to be perfected thereby, and means for feeding a narrow width web twice between the upper bed and cylinder, and means for deflecting and turning the narrow web so it will be perfected in its second 100 passage between said bed and cylinder, substantially as described. 105

9. In combination, three printing couples, each consisting of a bed and co-acting impression cylinder, means for directing a full width web between two of the lower printing couples to be perfected thereby; and means for passing a narrow width web twice in the same direction between the third printing couple, substantially as described. 110

10. In combination, three printing couples arranged 115 parallel one above the other each consisting of a bed and co-acting impression cylinder, means for directing a full width web between two printing couples to be perfected thereby; means for directing a narrow width web twice in the same direction between the third printing couple, and 120 means for deflecting and turning said narrow web, substantially as described.

11. In combination, three printing couples arranged parallel one above the other, each consisting of a bed and co-acting impression cylinder; means for directing a full 125 width web between two printing couples to be perfected thereby, means for directing a narrow width web twice in the same direction through the third printing couple, means for feeding such web twice to said couple, and delivering it twice therefrom, and means for deflecting and 130 turning said narrow web between the point where it is first delivered from and the second time fed to said couple, substantially as and for the purpose described.

In testimony that I claim the foregoing as my own, I affix my signature in presence of two witnesses.

HENRY F. BECHMAN.
